UNITED STATES PATENT OFFICE

EDWIN G. SCHLOSS AND MYRON J. SCHLOSS, OF NEW YORK, N. Y.

DESIGN FOR A COMBINED FOLDING BAR AND RADIO CABINET

Application filed August 24, 1932. Serial No. 44,686. Term of patent 3½ years.

To all whom it may concern:

Be it known that we, EDWIN G. SCHLOSS and MYRON J. SCHLOSS, citizens of the United States, residing in New York, in the county of Bronx and the State of New York, have invented a new, original, and ornamental Design for Combined Folding Bar and Radio Cabinet, of which the following is a specification, reference being made to the accompanying drawings, forming part thereof, in which—

Fig. 1 represents a perspective view of the

combined folding bar and radio cabinet made in accordance with our invention, and

Fig. 2 represents the combined folding bar and radio cabinet in a folded position.

The rear portion of the cabinet is substantially plain and unornamental.

We claim:

The ornamental design for a combined folding bar and radio cabinet as shown and described.

EDWIN G. SCHLOSS.
MYRON J. SCHLOSS.
